UNITED STATES PATENT OFFICE

EARL W. PETERSON, OF CHICAGO, ILLINOIS

ELEVATOR INSTALLATION

Application filed January 8, 1929. Serial No. 331,037.

My invention relates to the installation of doors in elevator shafts, and more particularly to means for protecting the door hangers from dust and extraneous interference, 5 and my main object is to provide a novel cover for the hanger compartment which is easily removable.

A further object of the invention is to so dispose the novel cover that it may be 10 loosened for removal by a short and simple motion.

A still further object of the invention is to so design the cover and the receptacle therefor that the cover may be accessible for removal from a convenient position in the elevator cab.

Another object of the invention is to provide the novel cover with a bearing whereby to retain the cover compactly against the 20 frame work of the hanger compartment, so that the cover may at no time be in the way of the cab.

A final, but nevertheless important object of the invention is to construct the novel cover 25 along lines of extreme simplicity whereby to make its cost nominal and its application easy.

With the above objects in view and any others that may suggest themselves from the 30 specification and claims to follow, a better understanding of the invention may be had by reference to the accompanying drawing, in which—

Figure 1 is a vertical section of a typical elevator door installation, showing the positions of the novel cover both as installed and as about to be removed;

Fig. 2 is a fragmentary elevation of the door installation at one of the upper corners, the view being directed from the right hand 40 side of Figure 1.

Fig. 3 is an elevation of the installation on a smaller scale as viewed from the interior of the elevator cab; and

Fig. 4 is a perspective view of the novel cover.

In modern elevator door installation, the space above the doors and which contains the hanger mechanism, faces the shaft. This 50 space or compartment is usually closed to the

view by a cover plate, the conventional plate being one that is hinged to open outwardly. When this plate is opened, access is had for the purpose of lubricating the door hanger, and usually access for opening the plate is 55 had by lowering the cab to a sufficient extent that a mechanic standing upon the cab may have handling access to the cover; also, this operation is necessary because the cover is usually much longer than the cab entrance 60 and cannot therefore be swung out sufficiently by access from within the cab. Granting that the hanger has been attended to, it is often the case that the cover is left open or is imperfectly closed with the result that it is 65 jarred open from the operation of the doors. In this event, the cover projects in the way of the moving cab and is apt to be damaged or even entirely broken off by the impact of the cab. It has been my intention to depart 70 from the deficiencies of covers used in the past and to provide a cover which is efficient and fulfills the above stated objects in every particular.

Referring specifically to the drawing, 10 75 denotes as a matter of example a set of two-speed doors in a typical elevator installation. In connection with these, a simple hanger installation 11 is shown, the compartment or housing therefor being indicated at 12, and the facing plate at 13. The facing plate is coincident with the front wall of the shaft, and the cab 14 moves and opens along a path 80 in close proximity to such wall.

The housing 12 is made with conventional 85 brackets 15 to serve as a backing for a cover or enclosure for the hanger compartment, the novel cover being indicated at 16. As more clearly shown in Figure 4, this cover is constructed from a length of stiff sheet metal, 90 being made with a downward hook flange 16^a along its top edge and with a deflected portion 16^b toward the lower edge, such edge being formed with a channel flange 16^c. Considering the cover as viewed from the 95 cab, the hook flange 16^a is frontally directed, while the deflected portion 16^b is in a rearward direction; and the channel 16^c is in the nature of a trough and extends along the rear side of the cover.

The novel cover is made in a main length, indicated by the numeral 16, and with an extension 17, as shown in Figure 3. The main length 16 covers the greater portion of the hanger mechanism, such portion being the one which requires the most frequent lubrication and attention; and the extra length may be considered as covering that portion of the hanger installation which requires but occasional lubrication and attention. My reason for constructing the novel cover plate with the main and extended sections in separate bodies is to facilitate the removal of the main and more frequently serviced portion of the cover plate by handy access from within the cab. Thus, it is not necessary to have the mechanic mount the top of the cab and direct the operator to adjust the position of the cab to the proper level for access to the main portion of the cover.

In order to install the novel cover, I form the lower edge of the facing plate 13 with an up-turned hook flange 13^a, such flange being rearwardly directed when considered as viewed from the cab. It is my intention that the cover be suspended from the facing plate by hooking the flange 16^a of the cover into the flange 13^a of the facing as denoted by full lines in Figure 1. By proper machine methods, the flanges may be pressed whereby to engage with a fairly snug fit, so that they will not be subject to vibration yet will not require more than ordinary strength to disengage them in case the cover is to be removed. After the cover has been hooked as described it may be secured against accidental departure by applying screws 18 by way of holes 18^a made in the cover to enter tapped holes made in the brackets 15, the application of such screws serving to dispose the cover in rigid position. The deflected portion 16^b and the channel 16^c of the cover serve to catch and confine any excess lubricating material which may be discharged from the hanger mechanism in the direction of the cab.

When the hanger mechanism is to be lubricated or otherwise attended to, it is an easy matter for the mechanic to approach the screws 18 from within the cab 14 whether the doors 10 are open or closed, since the position of the screws is well within the sphere of the door opening. Once the screws have been removed, one or two light blows in an upward direction will unhook the cover whereupon it may be drawn forwardly as indicated by dotted lines in Figure 1, and lowered in tilted fashion to clear the expanse of the door opening in the cab for the convenient transfer of the cover to the cab. Attention to the hanger is thus immediately had by reason of the intimate exposure of the hanger compartment and the fact that the cover is entirely out of the way. This method of removing the main portion of the cover,

which is of a length in excess of the door opening, actually exposes such a length on the part of the hanger mechanism with the result that the greater or more important portion of such mechanism may be fully lubricated 70 or otherwise serviced without the necessity of climbing upon the cab, special handling of the latter by the operator, and the delay so incurred. Also the removal of the cover allows clearance when hanging the doors. 75

After the hanger has been serviced in the manner described and the cover restored and secured in place, it will not be evident to those traveling in the cab that any special function is suggested by the cover plate. In 80 other words, the latter is extremely neat in appearance and in its relation to the facing plate 13; and, being of excess length in its main portion, its ends or breaks from the extensions 17 are not visible to those riding in 85 the cab.

The method of applying the cover also enables it to be shifted sidewise by simply removing the screws 18 in case it is not desired that the cover be entirely removed so that 90 but a portion of the mechanism may be exposed if desired by a partial shift of the cover. Also, it may be advisable to reverse the directions of the co-acting hook flanges 13^a and 16^a, whereby to dispose the cover exteriorly 95 of the facing plate 13; and further, it may be advisable to dispose the main and extended portions of the cover telescopically. However, these modifications may be but incidental to the specifications laid out for the 100 installation in specific instances, and may be considered as secondary, since they do not essentially depart from the spirit of my invention.

In conclusion it may be said that the novel 105 cover is an appliance of extreme simplicity, and is capable of application without causing an appreciable departure from standard elevator design. The method by which it is serviced precludes the possibility of defective or insufficient mounting whereby to detract from the safety factor of the appliance, since the cover is always in full view of the elevator operator and can be checked as to proper installation immediately. Should the 110 cover by any chance become damaged, it is a matter of trifling expense and service to replace it by a new one.

While I have illustrated and described the 115 invention in the preferred form, it will be evident that the same is capable of many minor changes and refinements and it is my intention to include such changes and refinements as coming within the spirit and scope 120 of the appended claims.

I claim:

1. A closure for a door hanger installation, comprising a facing for the installation, brackets opposite the facing, and a 130

cover plate detachably hooked to the facing and secured to the brackets.

2. A closure for a door hanger installation, comprising a facing for the installation and formed with an up-turned base flange, and a cover plate formed with a down-turned top flange, said cover plate being suspended from the facing by the interfitting engagement of said flanges, said cover plate being removed only during repairs and lubrication of said installation.

3. A closure for a door hanger installation comprising a facing for the installation and formed with an up-turned base flange on the side opposite the installation, and a cover plate formed with a down-turned top flange on the side remote from the installation, said cover plate being suspended from the facing by the interfitting engagement of said flanges.

4. An invisibly-joined cover for the hanger of an elevator door installation comprising a main cover plate opposite the course of the cab entrance and wider than the latter, and a completing extension of said plate applied laterally of said main cover plate.

5. A closure for the hanger compartment of an elevator door installation, comprising brackets in said compartment and spaced within the course of the cab entrance, a cover plate applicable to said brackets, and fastening devices directed through said cover plate into said brackets.

6. A closure for the hanger compartment of an elevator door installation, comprising an elongated plate, suspending means for the latter along its top edge, a lower portion deflected in the direction of the compartment, and a channel trough internally formed at the bottom of said lower portion to serve as a receptacle for excess lubricant.

In testimony whereof I affix my signature.
EARL W. PETERSON.
